ABSTRACT OF THE DISCLOSURE

A drill bucket is suspended by means of a fastening system adapted to hold the bucket against vertical motion, before actuating the bucket shells, by bearing against the walls of the shaft being drilled.

Grab bucket devices are already known for drilling prismatic- or circular-sectioned wells or shafts.

In certain known devices of this character the bucket is caused to penetrate or dig the ground by causing the excavator boom to exert a pressure on the bucket. However, this method is applicable only to specific cases wherein the well or shaft to be made is of relatively reduced depth. If a substantial depth is required the bucket must be suspended from a rope and the penetration is obtained in some cases by allowing the bucket to fall freely from a certain height, this method requiring a heavy and sturdy bucket. Moreover, the heterogeneous structure of the ground may tend to deflect the line of fall of the bucket from a straight line, thus compromising the balanced conditions of operation of the two bucket shells.

Another known device consists in causing the bucket to penetrate like a drill into the ground with the assistance of a to-and-fro motion obtained from a complicated hydraulic or mechanical assembly, and reclosing the shells after a predetermined degree of sinking has been attained.

It is the object of this invention to provide a drill bucket which is both particularly simple in construction and perfectly reliable in operation.

To this end, this drill bucket is suspended by means of a fastening system adapted to hold the bucket against vertical motion, before actuating the shells, by bearing against the walls of the shaft.

The features and advantages characterizing this invention will appear more completely from the following description given by way of example with reference to the diagrammatic drawing attached hereto, wherein:

FIGURE 1 shows in axial section the bucket lowered to the bottom of the well or shaft being dug.

FIGURE 2 shows the same bucket after the locking in position of the fastening system.

FIGURES 3 and 4 are plan views showing the different forms of embodiment of the fastening system in the position shown in FIGURE 2.

The bucket 1 of a conventional type is actuated by means of a hydraulic cylinder 2 the expansion and contraction of which cause the closing and opening of the pair of shells 3 of the bucket by means of arms 4. In FIGURE 2 the shells are shown in their open position in thick lines (at 3) and in their closed position in dash lines (at 3a). These shells may be shaped for drilling a cylindrical or prismatic-sectioned well.

This bucket 1 is suspended from a rope 11 by means of a fastening system comprising essentially at least two guide plates 5 of a shape consistent with the cross-sectional contour of the projected shaft or well (assumed to be circular in this example). These guide plates 5 are pivotally connected for example on the one hand to the body 6 of a single- or double-acting cylinder 6 by

2

means of links 7 and on the other hand to the piston rod 8 of this cylinder by means of another set of links 9. These guide plates 5 are suspended from the lower end of a suspension and operating rope 11 by means of slings 13 attached to the pivot points of the outer ends of the upper links 9. In case the cylinder 6, 8 is of the single-acting type, traction springs 10 will contract the cylinder assembly and hold the fastening system in the retracted position shown in FIGURE 1 when no fluid under pressure is supplied to this cylinder.

10 The bucket thus suspended from the fastening system operates as follows:

The bucket positioned as shown in FIGURE 1 is lowered into the then completed shaft portion until the shells 3 contact the bottom thereof. Then the cylinder 6, 8 is expanded and the guide plates 5 are pressed against the walls 12 of the shaft. Expanding the cylinder 2 will then move the shells 3 to the position 3a of FIGURE 2, thus filling the bucket with material to be rejected. The cylinder 6, 8 is subsequently contracted to move the guide plates 5 away from the walls 12 of the well, and the bucket 1 may be raised by pulling the rope 11 and its contents is finally discharged externally of the shaft.

20 The hydraulic control device for actuating the cylinders 2 and 6, 8 may be constructed with a view to produce mutually synchronized movements, or servo-action movements or independent movements, at will.

25 In drillings in firm grounds not requiring the casing of shafts, the guide plates 5 engage the walls directly. 30 If the ground is soft or such as to require the use of casing elements to be lowered as the drilling progresses, the guide plates 5 bear on the previously fitted casing portion.

35 Of course, many modifications may be brought to the constructional details described hereinabove with reference to the drawing without departing from the spirit and scope of the invention as set forth in the appended claims.

What I claim is:

40 1. A drilling apparatus comprising a bucket consisting of a hydraulic-operated cylinder having a bearing element and a working element movable in relation to said bearing element, shells pivoted on said bearing element, links pivoted on said shells and said working element of said cylinder, a fastening system supporting said bearing element of the bucket cylinder, means for suspending said fastening system, said fastening system comprising a hydraulic control cylinder having a lower end connected to the bearing element of the bucket hydraulic cylinder and an upper end, surface guide members corresponding 45 in shape to sectors of the wall of the shaft being drilled, links having outer ends pivotally connected to said surface guide members and inner ends pivotally connected to the lower and upper ends, respectively, of said hydraulic control cylinder, the operation of said control cylinder in the direction to reduce its length freeing said guide members from the shaft being drilled, the operation of said control cylinder in the direction to increase its length causing said guide members to be locked together with the complete fastening system on said sectors of the shaft wall.

50 2. A drilling apparatus as set forth in claim 1, wherein said cylinder for controlling said fastening system is a double-acting cylinder.

55 3. A drilling apparatus as set forth in claim 1, wherein in said fastening system comprises spring means attached to both ends of said control cylinder and constantly urging same to its retracted position in which said control cylinder releases the surface guide members from the wall of the shaft being drilled, said control cylinder being a single-acting cylinder operative only in the expansion direction.

4. A drilling apparatus as set forth in claim 1, where-
in said means for suspending the fastening system con-
sist of suspension slings attached to the pivot points in
said surface guide members of the aforesaid links pivoted
on the other hand to the upper end of said cylinder con-
trolling said fastening system.
